(**) Term: **15 Years**

(21) Appl. No.: **29/743,054**

(22) Filed: **Jul. 17, 2020**

CLAIM**Related U.S. Application Data**

(62) Division of application No. 29/647,569, filed on May 14, 2018, now Pat. No. Des. 906,364.

DESCRIPTION**Foreign Application Priority Data**

FIG. 1 is the first image in a sequence for a display screen or portion thereof with transitional graphical user interface showing our new design;

Feb. 13, 2018 (KR) 30-2018-0007591
(51) LOC (13) Cl. 14-04

FIG. 2 is the second image thereof;

(52) U.S. Cl. ..... USPC D14/488

FIG. 3 is the third image thereof;

(58) Field of Classification Search ..... USPC D14/485-495
USPC ..... CPC G06F 3/0485; G06F 2203/04806; G06F

FIG. 4 is the fourth image thereof;

3/04847; G06F 1/1692; G06F 2203/04807; H04N 1/0044; H04M 1/2477

FIG. 5 is the fifth image thereof; and,

See application file for complete search history.

FIG. 6 is the sixth image thereof.

References Cited

The outer perimeter illustrated by a pair of dashed broken lines in the drawings illustrates a display screen or portion thereof and forms no part of the claimed design. The remaining broken lines in the drawings illustrate portions of the transitional graphical user interface that form no part of the claimed design.

U.S. PATENT DOCUMENTS

The appearance of the transitional image sequentially transitions between the images shown in FIGS. 1-6. The process or period in which one image transitions to another image forms no part of the claimed design.
